US0D1105142S

(12) **United States Design Patent** (10) Patent No.: **US D1,105,142 S**
 Stusynski et al. (45) Date of Patent: ** Dec. 9, 2025

(54) DISPLAY SCREEN OR PORTION THEREOF WITH GRAPHICAL USER INTERFACE	4,829,616 A	5/1989	Walker
	4,890,344 A	1/1990	Walker
	4,897,890 A	2/1990	Walker
	4,908,895 A	3/1990	Walker
(71) Applicant: Sleep Number Corporation , Minneapolis, MN (US)	D313,973 S	1/1991	Walker
	4,991,244 A	2/1991	Walker
	5,144,706 A	9/1992	Walker et al.
	5,170,522 A	12/1992	Walker
	5,430,266 A	7/1995	Austin, Jr. et al.
(72) Inventors: Stacy Stusynski , Blaine, MN (US); Russell Hampton , San Francisco, CA (US); Kelsey Kong , San Francisco, CA (US); Kristen Elizabeth Swenby , Blaine, MN (US); Julie Elepano , Minneapolis, MN (US); Carol Lynn Herman , Minneapolis, MN (US)	D368,475 S	4/1996	Scott
	5,509,154 A	4/1996	Shafer et al.
	5,564,140 A	10/1996	Shoehair et al.
	5,642,546 A	7/1997	Shoehair
	5,652,484 A	7/1997	Shafer et al.
	5,765,246 A	6/1998	Shoehair
